UNITED STATES PATENT OFFICE.

WILLIAM EBENEZER ELLIOTT, OF LIVERPOOL, ENGLAND, ASSIGNOR TO MERGEN-
THALER LINOTYPE COMPANY, A CORPORATION OF NEW YORK.

MATRICES OF TYPOGRAPHICAL COMPOSING AND DISTRIBUTING MACHINES FOR DISPLAY-WORK, HEAD-LINES, AND THE LIKE.

1,158,663.

Specification of Letters Patent.

Patented Nov. 2, 1915.

Original application filed July 16, 1913, Serial No. 779,409. Divided and this application filed July 14, 1914.
Serial No. 850,864.

To all whom it may concern:

Be it known that I, WILLIAM EBENEZER ELLIOTT, a subject of the King of the United Kingdom of Great Britain and Ireland, residing at 133 Salisbury road, Wavertree, Liverpool, in the county of Lancaster, England, have invented new and useful Improvements in the Matrices of Typographical Composing and Distributing Machines for Display-Work, Head-Lines, and the like, of which the following is a specification.

The present invention consists of improvements in the matrices of typographical composing and distributing machines for display work, head lines, and the like, such as the lines of displayed advertisements or of title pages; the head lines of news columns in newspapers; or of articles in periodicals or serial magazines; and the like. It is especially applicable to machines now known commercially under the trade mark "Linotype" if they have more than one magazine. Such a machine composes a line in the desired face or faces, uses it, and then distributes it. A patent for the United States on a machine so known is No. 436532, September 16th, 1890, and it described a machine equipped with a single magazine and a single face.

A multiplicity of magazines and of faces, have been added by subsequent patents. The above mentioned use was to be one of matrices from which printing bars (now commonly known as slugs) were to be cast, or of type dies such as would indent a flong. The former of these two uses, is the only one to which the machine has been actually put; nevertheless, the terms "matrix", "matrices", are hereinafter to be understood as respectively including "type die" and "type dies."

The present application for Letters Patent is a division from my application filed July 16th 1913, Serial Number 779409, on my invention of "Improvements in typographical composing and distributing machines for display work, head lines, and the like", and is strictly limited to the hereafter

described improvements in the matrices of such machines. It has been found necessary to include a description of the immediately coöperating organs of the machine, because their omission would have left certain features of the present invention in doubt, but such inclusion in no way implies the inclusion of those organs in the said invention.

The improved matrices of the present application and the improved magazines of the application mentioned in the preceding paragraph differ from those of the commercial machine above referred to by the former lying in and passing through the latter on the flat instead of in an edge-up position.

The matrices are further distinguished from those of the said machine by their lugs being capable of selecting in respect to distribution for font, the particular magazine from which the respective matrices had been composed and into which they must be returned, by reason of the lugs of one font being at a level either higher or lower than that of the lugs of any other font. As an aid to the separation of the matrices in respect of distribution for font into groups of fonts, the matrices of one group have flat sides and all the other matrices have grooved sides, both flat sides and grooved sides coöperating with rails alined with the direction in which the matrices move, whereby the grooved matrices, because they straddle the rails, are separated from the flat side matrices which cannot so straddle the said rails, into another group of fonts. Thus one depth of grooving and one set of rails effects a separation of all the matrices into two groups of fonts. If separation into a greater number of groups is required, the depth of grooving is increased in each additional group and there is an additional set of rails for each such group, the sets being alined with each other in the direction above mentioned.

A matrix issuing from its groove in the magazine entrance, slides down over the rails toward the magazines of the top group,

if its bottom face is not grooved; but if it is grooved, the grooves straddle the rails, and the matrix slides down toward the magazines of the bottom group. The magazines 5 of a group are distinguished from each other by the level at which a pair of ledges project inwardly from the sides of the respective magazine, one ledge from each side and opposite its fellow ledge. The level of any 10 given pair of ledges is the level of the under side of the magazine-selecting lugs on the matrices belonging to the respective magazine, so that as a matrix comes up to the entrance mouth of its group, its lugs 15 will select its proper magazine out of the four otherwise open to it by sliding onto the respective pair of ledges.

A matrix escapement is of the usual two pawl type adapted to coöperate with the 20 two lugs on one side edge of a matrix, by being wholly within the magazine and pivoted on the side of the respective magazine groove.

Referring to the accompanying drawings: Figure 1 is a plan of an improved matrix as it lies in its magazine channel; Fig. 2, an inverted plan of an improved matrix grooved in its bottom side; Fig. 3, a front elevation of four matrices of the 25 ungrooved group, and lugged at four different levels for as many magazines; Fig. 4, a front elevation of four matrices of the grooved group and lugged at four different levels for as many magazines. These four 30 figures are on an enlarged scale. Figs. 5 and 5^a taken together, a sectional side elevation including key-board, assembler, column of magazines and distributer; and Fig. 6, a sectional rear elevation of the entrances 35 to the magazines of an eight magazine machine showing the matrices divided into two groups and each group subdivided by the lugs of the matrices.

1, 1 are matrices of one group and 2, 2 45 matrices of the other group. They differ from the matrices of the commercial machine above identified in the following three respects, although otherwise they are of the regular construction, each containing at its 50 upper end the usual tooth combination to distribute it according to character.

First—so long as they are within or are 55 passing through their magazines they are on the flat as indicated in Figs. 1 and 2 and shown in Figs. 6, instead of edge up.

Second—a certain proportion of the fonts of matrices—say one half—is separable as a group from the other fonts, by having longitudinal grooves 3, 3, in the bottom 60 sides of all the matrices. The object of these grooves is to enable the matrices to straddle the same number of rails 4—Fig. 5 (obviously, only one of them is visible, the other standing behind it). These rails are

fixed to the column of magazines 5 to 12 in such a way as to be alined with the travel of the matrices as they approach the entrance mouths 13 to 20 of the magazines on their way thereto from the distributer 21. The matrices of the other fonts, have their 70 bottom sides ungrooved, *i. e.* flat as heretofore, the object of the absence of grooves being to prevent them straddling the said rails 4. Thus when one half of the matrices is grooved and the other half not grooved, 75 there are produced two groups—1 and 2—see Figs. 1 to 4 and 6.

Third—The lugs 22 (two projecting from each side edge as heretofore) are capable of selecting, for the purpose of the final distribution of the matrices, the particular one of the magazines 5 to 12, from which they were composed and into which it is required that they should be returned. This capacity is secured to them by the lugs 22 of each 80 matrix of a font being at a level either higher or lower than that of the lugs of any other font. This difference in level is clearly shown *per se* in Figs. 3 and 4.

The number of groups into which the 90 fonts of matrices is divided depends fundamentally upon the thickness of the matrices. It has been assumed that as the matrices—being for display work, head lines, and the like—are thick, they are thick enough for 95 their lugs 22 to be at four levels. The criterion for the number of these levels is the thickness of the ledges (described farther on) in the matrix channels and with which the lugs 22 coöperate to effect the selection above 100 described, together with the maintenance of sufficient strength in the said lugs to withstand all the strains to which they will be subjected as they pass through the machine. Further, it has been assumed that there are 105 eight magazines in the column. Eight divided by four settles the number of groups as two. If there had been twelve magazines, that number would have been three, if the number of levels were three, the number of groups would be two with six magazines and three with nine. If the division of magazines by levels leaves a remainder, the latter constitutes a group having the remainder number of levels. 110

The reason why there are two grooves in a grooved matrix is that one would not prevent a matrix tipping out of the flat and that more than two are not required to keep it in that position. 115

The magazines are laid together in the form of a column in the well known way, and are not vertically adjustable for change of font. There is only one distributer 21 for all the magazines of this column and 125 this is of the well known permuted bar and traversing screw construction for distributing matrices according to character. The

matrices travel along it in the usual way and drop from it as heretofore into the respective channels of a general magazine entrance 23 common as heretofore to all the 5 magazines in the column. Each of these channels is twisted through a quarter of a circle as indicated at 24 in Fig. 5, to enable it to turn the matrices sliding down it from the edge-up position which they have when 10 they enter the said entrance 23 into the on-the-flat one already described.

Any matrix issuing from its channel in the magazine entrance 23, slides down the rails 4. The ungrooved matrices 1 of one 15 group being restricted by the absence of grooves to sliding corporeally above the said rails slide off them on to a rearward extension 25 of the bottom plate of the top group of magazines 5 to 8. The grooved 20 matrices 2 of the other of the two groups (it has been pointed out that only two groups are provided for by the illustrated construction) slide down the rails 4, it is true, but, because of their grooves 3, they 25 straddle these rails so that only that portion 26 of their thickness—see Fig. 4—which the said grooves leave them, is then corporeally above the rails 4, and their bottom sides practically too low to slide into 30 the extension 25. There is, therefore, no alternative for them but to slide through the port 27 between the rails 4 above and the extension 25, on to a rearward extension 28 of the bottom plate of the bottom group, 35 of magazines 9 to 12. Thus one depth of grooves 3 in half the fonts of matrices, divides the latter into two groups. In other words, the number of groove depths and of the coöperating ports, is one less than the 40 number of groups into which the fonts are to be divided. If three groups were required there would be two different groove depths, three groups of magazines, and a second pair of rails, a second port, and a second extension between the rails 4 and the 45 extension 25 to conduct the fonts grouped from the other fonts by the intermediate groove depth into the intermediate group of magazines.

50 The grouped matrices slide over the extensions 25, 28 to the entrance mouths 13 to 20 of their respective magazines 5 to 12, and there each meets the devices with which the lugs 22 coöperate to select the magazine to 55 which the respective matrix belongs. These devices consist of a ledge 29—Figs. 5 and 6—projecting inwardly from each side 30 of each entrance mouth 13 to 20 and of each matrix channel 31 in a magazine, excepting 60 in the case of one row of those mouths and channels. The excepted row may be either the top or the bottom one of a group of them. According to the constructional form illustrated, it is the bottom one. One lug 29

is exactly opposite its fellow lug in both 65 mouth and channel and their common width such that the matrices shall slide by their lugs 22 smoothly over them. The matrices that have entered the general magazine entrance 23 having been divided into groups 70 by the rails 4, any matrix proceeds to automatically select and enter the magazine to which it belongs. Thus, those that had been composed from magazine 8 have their lugs 75 22 flush with their bottom sides. These, therefore, miss all the ledges 29 and slide on to the plate 33 which extends from one side of the column of entrance mouths 13 to 20 and magazines 5 to 12 to the other, thereby dividing them into two groups and 80 from there on to the bottom plate 34 of their matrix channel 31 in the respective magazine. And those that were composed from magazine 5 have their lugs 22 at a level proper for engaging on the top pair of 85 ledges 29 and slide along them until they are over and on the bottom plate 34 of their matrix channel 31 in the respective magazine.

The sides of the matrices which contact 90 with the rails 4 are hereafter referred to as the operative sides to distinguish them from the top sides which are not affected by, nor concern, the invention.

It will be understood, of course, that the 95 lugs 22 and the grooves 3 may be used to distinguish matrices of different fonts without necessarily following the mode of procedure above outlined; that is to say, the grooves might be employed to distinguish 100 between two fonts instead of between two groups of fonts as herein; and similarly the lugs might be employed to distinguish between two or more fonts irrespective of whether such fonts are separated first according to group.

A matrix escapement lever 36—Fig. 5^a—has the usual two pawls 37 adapted to co-operate with the two lugs 22 on the respective side edge of a matrix by being wholly 110 within the respective matrix channel and pivoted upon the respective side wall 30. The front ends of the levers of each column of matrix channels, are connected to a link 39 working in the well known way in a 115 plane at right angles to the slope of the magazines and through the latter, each link being normally depressed by a spring 40 to lock the respective matrices back and having its bottom end operatively connected to 120 the top end of the usual escapement rod 41 that connects the said column of levers 36 with the keyboard 42 in the usual way.

Having described my invention, I declare that what I claim and desire to secure by 125 Letters Patent is:

1. A font of matrices having distributing combinations and lugs, the latter adapted to

- select the respective magazine during the process of distribution by their being at a level either higher or lower than that of the lugs of another font.
5. 2. A plurality of fonts of matrices having distributing combinations and lugs, the latter adapted to select the respective magazines during the process of distribution by the lugs of each font being at a level either 10 higher or lower than that of the lugs of any other font.
15. 3. A font of matrices having longitudinal grooves extending throughout in their operative sides and distinguishing it from a different font.
20. 4. A font of matrices having grooves extending throughout their operative sides and alined with the direction in which they will move during the process of distribution and distinguishing it from any other font.
25. 5. A plurality of matrix fonts distinguished from each other by the matrices of one font having their operative sides flat, and those of the other fonts having their operative sides grooved throughout in the direction in which the matrices will move during the process of distribution.
30. 6. A plurality of matrix fonts distinguished from each other by the matrices of each font being grooved to a depth different from that in the matrices of any other font, all the grooves extending throughout the operative sides of the matrices and being alined with the direction in which they will 35 move during the process of distribution.
40. 7. A plurality of matrix fonts distinguished from each other by the matrices of one font having their operative sides flat and those of the other fonts having their operative sides grooved throughout in the direction in which they will move during the process of distribution, the grooved fonts differing from each other by their grooves being different in depth.
45. 8. A font of matrices having grooves extending throughout their operative sides and distinguishing it from another font and lugs adapted to select the respective magazine during the process of distribution, by their 50 being higher or lower than those of another font.
55. 9. The combination of two groups of matrix fonts distinguished from each other as to group by the matrices of one group having flat operative sides and those of the other group having grooved operative sides and by all the matrices of each group having lugs adapted to select the respective magazine during the process of distribution, 60 by those of each font in the respective group being in a plane either higher or lower than that of the lugs of another font in the same group.
65. 10. A plurality of groups of matrix fonts distinguished from each other as to group by the matrices of each group having their operative sides grooved more deeply than those of the matrices of any other group, all the matrices of each group having lugs adapted to select the respective 70 magazine during the process of distribution, by those of each font in the respective group being in a plane either higher or lower than that of the lugs of another font in the same group.
75. 11. A plurality of groups of matrix fonts distinguished from each other as to group by the matrices of one group having flat operative sides and those of all the other groups having grooved operative sides, the 80 grooves in the several groups differing in depth, all the matrices of each group having lugs adapted to select the respective magazine during the process of distribution, by those of each font in the respective 85 group being in a plane either higher or lower than that of the lugs of another font in the same group.
12. A plurality of fonts of type or matrices each having a distributing combination and formed with a guiding portion on its edge, the said guiding portions being located in different setwise positions on the matrices of the respective sets.
13. A plurality of fonts of type or matrices divided into groups, at least one group comprising a plurality of fonts, and the type or matrices of all the fonts having the same character distributing combinations and distinguished from each other in 95 form both as to group and individual font.
14. A type or matrix having a distributing combination and formed with guiding lugs, the said lugs being located on the matrix in a different setwise position from 100 those of another type or matrix.
15. A plurality of type or matrices each having a distributing combination and formed with a guiding lug on its edge, the said guiding lugs being located in different 105 setwise positions on the respective matrices.
16. Two type or matrices, one formed in its side face with a groove extending throughout the length thereof, and the other having its side face plain or flat, for the 110 purpose described.
17. A plurality of type or matrices each having the same distributing combination and divided into groups, at least one of which comprises a plurality of type or 115 matrices, the type or matrices of one group differing in form from those of another group, and the type or matrices of a group differing in form as to each other.
18. A plurality of type or matrices each having the same distributing combination and divided into groups, at least one of which comprises a plurality of type or 120 matrices, the type or matrices of one group differing in form from those of another group, and the type or matrices of a group differing in form as to each other.
125. 19. A plurality of type or matrices each having the same distributing combination and divided into groups, at least one of which comprises a plurality of type or matrices, the type or matrices of one group differing in form from those of another group, and the type or matrices of a group differing in form as to each other.

matrices, the type or matrices of one group being distinguished from those of another group by grooves formed in their side faces, and the type or matrices of a group being distinguished from each other by lugs formed on their edges and located in different setwise positions thereon.

In witness whereof I have hereunto set my hand in the presence of two witnesses.

WILLIAM EBENEZER ELLIOTT.
